(57) **CLAIM**

The ornamental design for an external catheter, with bridges, for a female user, as shown and described.

DESCRIPTION

FIG. 1 is a side view of the external catheter, with bridges, for a female user.

FIG. 2 is a top view of the external catheter, with bridges, for a female user.

FIG. 3 is a front view of the external catheter, with bridges, for a female user; and,

FIG. 4 is a perspective view of the external catheter, with bridges, for a female user.

The broken line showing of parts of the drawings is included for the purpose of illustrating use and environment and forms no part of the claimed design.

The claimed ornamental design for an external catheter, with bridges, for a female user described herein is embodied in an external catheter, with bridges, for a female user.

1 Claim, 4 Drawing Sheets

FIG. 1

FIG. 2

FIG. 3
